LEAD ASSEMBLY

William A. Uline and Howard P. Rowell, Sidney, N. Y., assignors to Bendix Aviation Corporation, New York, N. Y., a corporation of Delaware

Application March 7, 1946, Serial No. 652,566

6 Claims. (Cl. 173—363)

1

This invention relates to a lead assembly of the type adapted to transmit an electric current, particularly comprising an insulated conductor wire attached at its ends to appropriate electrical contacts or connectors and protected by a hose attached at its ends to appropriate fittings, and further relates to means of completing such an assembly, to means of dismantling it, and to a novel process therefor.

Heretofore, lead assemblies have been made but they have been subject to the fault that there was no method by which a cable could be assembled within protective hose equal in length thereto, especially when the lead assembly is short and the outer diameter of the cable approximates the inner diameter of the hose. Consequently, the devices of the prior art depended upon compressible springs, upon slack in cables of excess length, or upon hose fittings of particular design to compensate for the unequal length of hose and cable. Those devices were relatively inefficient in operation and high in cost.

It is an object of this invention to make a lead assembly in which hose and cable are of substantially the same length, so that in assembled relation the contacts are in correct relation to the fittings and the cable is substantially without slack. Each hose may contain one or several leads.

Another object of the invention is to assemble such a lead assembly.

Another object of the invention is to dismantle such an assembly.

Yet another object of the invention is to devise tools for assembling and tools for dismantling the cables and hoses of electrical leads.

Still another object is to make a lead of novel construction free from unsealed joints, in which all parts are mounted as an integrated inter-supported whole having novel means for positioning the connectors within fittings of different design.

Other objects and novel features of the invention will be in part apparent and in part set forth in the accompanying specification.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

2

In the drawings, wherein like reference characters refer to like parts throughout the several views,

Fig. 1 is a vertical longitudinal section through a lead assembly embodying concepts of this invention;

Fig. 2 is a similar section through a hose end and a connector of the pin type;

Fig. 3 is a vertical section through an elbow fitting showing a step of the novel process, and a novel tool partly in section;

Fig. 4 is a similar section showing a later phase of the process, and details of a novel hose, elbow and fitting with cooperating cable and mounts;

Fig. 5 is a similar section showing a yet later phase of the process and another novel tool;

Fig. 6 is a part section through a novel dismantling tool;

Fig. 7 is a plan view of dismantling tongs; and

Fig. 8 is an end view of the tongs shown in Fig. 7.

Referring now to the numerals of the drawing and to Figs. 3, 4, and 5, which show a preferred form of the invention and disclose the process of assembly, 10 is a hose fitting having an elbow 11, a body portion 12 that is adapted to make contact through a spherical face 13 with a cooperating fitting, and an internally screw threaded nut 14 which is mounted on the body portion 12 by means of overlapping flanges 15 and 16. A hose ferrule 17, shown in Fig. 4 only, fits snugly within the end of the elbow 11 and is preferably attached thereto by soldering. The hose 19 contains an insulated cable 18 which with its attached contacts 20 is of length substantially equal to that of the hose and its fittings. It is to be understood that this equality need not be exact, the criterion being the production of an assembled unit having relative slack in neither cable nor hose. This is shown in Fig. 1 and is believed to be a construction unknown to the prior art. This construction permits the cable and the hose to be of substantially snug and mutually supporting fit, although in the drawings they are shown to be of different sizes for purposes of clarity and to illustrate the adaptability of the invention to variations in construction.

Such constructions were unknown to the prior art, and no methods were available by which they could be made. The novel constructions herein described were facilitated by the novel method that also forms a part of this invention. This novel method is illustrated in a preferred

form in Figs. 3, 4, and 5, but before describing the method there will be described certain tools which are adapted to facilitate the carrying out of the method. In those figures the numeral 21 refers to one part, of a two-part tool 21-25, having a hollow end 22 and a pointed end 23. The tool is adapted to distend a grommet 33 having small inner diameter to such size that it can pass freely over the connector 30 and the cable 18. The cooperating tool part 25 has a sliding fit over the part 21. The part 25 is tubular, having an elongated part 26 with a flat end 27 adapted to serve as a pusher. The opposite end 28 is internally enlarged at 29 for a certain depth, the enlargement being terminated by the abutment 30. The interior of the body portion 12 of the fitting has an annular abutment 31 and an annular abutment 32 spaced therefrom, the abutments and the cylindrical wall forming a cylindrical chamber with annular end walls.

For cooperation with that chamber in the mounting of the contacts in the fittings there are two flexible inserts 33 and 34, in the form of the invention shown in Figs. 3, 4, and 5, having external flanges 35, 36 of such size that, when they are firmly compressed one against the other, their flanges 35, 36 fit within the abutments 31, 32. The insert or bushing 33 is tapered to lend it increasing flexibility toward its small end. The inserts may satisfactorily be made of rubber or of other flexible and resilient material.

The contact 20 has a reduced portion 37. The insert 34, which is commonly called an insert by persons skilled in the art, is provided with an internal flange of size adapted to fit the reduced portion 37, both cooperating parts having square ends to prevent disengagement after assembly.

In assembling the device the hose and fittings may be first completed. All connections between the hose and fittings may be made by solder and without the use of unsealed joints, which constitutes a considerable advantage. In soldering the hose ferrule to the elbow or other connector, caution should be employed, when a rubber hose is employed, not to unduly overheat the hose ferrule 17.

When the hose has thus been prepared, a cable of correct length is selected, the ends of the wire are uncovered and cleaned, and one end is soldered in the solder well 38 of a contact 20.

In Figs. 3, 4, and 5 the contact is shown to be of receptacle or socket type, but it could be of pin type as shown at 24 in Fig. 2 if desired.

The cable thus having been soldered at one end to a contact, the free end is passed through the hose assembly until the attached socket contacts rest in the elbow of the cable, whereupon the second contact is attached to the other end of the cable as it projects from the hose into or beyond the fitting which is not shown in Figs. 3-5. The cable is returned to a balanced position within the hose and fittings, after the second connector has been attached, and the parts are ready for assembly as a unit.

The bushing 33 being adapted to fit either snugly to or with only slight spacing from the cable 18, could not normally be passed over the connector 20 without disturbing the relation of that connector to the fitting to such an extent that final adjustment would be impossible. However, by this invention the bushing is passed over the small end 23 of the tool 21, and arranged in distended position about the hollow end 22

thereof. The sleeve portion 25 of the tool is then passed over the part 21 and brought into abutting engagement with the end of the bushing 33. The connector 20 and the end of the cable 18 are then admitted to the hole in the tool as shown in Fig. 3, the part 23 of tool 21 is firmly grasped and the sleeve 25 is employed to thrust the bushing toward the position shown in Fig. 4. In attaining this position the elbow, the bracing effect of the hose, and the natural stiffness of the wire cooperate. The tool 25 is then removed and the insert 34 is passed over the tool 21. The tool 25 is then telescoped on the tool 21 in reverse position as shown in Fig. 4, and is employed to push the insert 34 into the position shown in Fig. 5 wherein the enlarged portion of inserts 33 and 34 fit within the chamber of the body portion 12 of the fitting. The cylindrical part 28 fits over the end of the insert and prevents it from expanding against the body 12 and stopping the progress of the insert.

By holding the tool 25 in position and withdrawing the tool 21 the distended grommet is permitted to conform itself to the shape of the contact 20, and by withdrawing the tool 25 the encircled part of the insert is released. In some instances this conformity may not be perfect in the first instance, in which case a tool 40 having a pin 41 is thrust into the contact, as shown in Fig. 5, which may then be accurately adjusted within the insert. When the final adjustment has thus been made, a substantially permanent and very precisely aligned connection exists between the hose and fittings and the cable and contacts.

One end of the unit having thus been assembled a similar procedure is applied to the other end, producing a unitary structure wholly new and possessed of great advantages.

When it is desired to dismount the inserts from the assembly, a tool such as shown in Fig. 6 may be employed. This tool consists basically of a hollow screw 50 whose spiral 51 may be of wood screw type and which is provided with a simple handle 52. Having placed the end of the screw within the end of the insert, it is turned and simultaneously advanced, whereby it distends the insert until it may be withdrawn in substantially undamaged condition from the contact and the fitting. Such withdrawn inserts usually may be used again. The inserts having been removed from one end of the assembly a pair of tongs 56 such as shown in Figs. 7 and 8 may be employed to further adjust the mounting at the other end, or if the inserts are withdrawn at both ends, to pull the wire through into such position that the assembly may be totally dismantled.

In Fig. 1 is shown an assembly wherein a single insert or grommet 57 replaces the two employed in the figures which have just been described. This figure also shows an assembly in which no elbow is employed and in which a metal tube 58 replaces the rubber hose hereinbefore described. This metal tube may be made of any satisfactory material but is preferably flexible.

The drawings show all the connecting nuts of the fittings to be internally screw threaded, but it is to be understood that the cooperating fittings would have externally screw threaded portions.

By means of this construction there is provided a lead which is without relative slack in its parts, which is protected against the disintegrating effects of vibration and shock, which can be assembled even though the concentric parts are

of substantially equal length, which can be dismantled with ease by the method and the employment of the novel tools described, and which has no unsealed joints. The structure, the method, and the tools are alike believed to be new and to constitute, together, a new conception of the constitution of connecting leads.

Although only a limited number of embodiments of the invention are illustrated and described in detail, it is to be expressly understood that the same is not limited thereto. As will now be apparent to those skilled in the art, various changes, such as in the design and arrangement of the parts illustrated, may be made in the illustrated embodiments of the invention without departing from the spirit and scope thereof. For a definition of the limits of the invention, reference is had primarily to the appended claims.

What is claimed is:

1. An electrical lead assembly comprising a single continuous length of hose, a unitary tubular fitting permanently secured to each end of the hose, a pre-molded resilient insert in and removable from each of said fittings, the latter having insert positioning means to cooperate with and resist removal of said inserts, at least one electrical contact extending through each of said inserts, the latter having contact positioning means for positioning and yieldably resisting removal of said contacts, and a cable in said tube having its ends permanently secured to the adjacent ends of the contacts supported in said inserts.

2. An electric lead including a tube, a rigid one-piece fitting fixed on each end of the tube, a resilient insert removably held under compression in each fitting, interior conformations on the fittings cooperating with exterior conformations on the inserts to position the inserts in the fittings and yieldably resist removal of the inserts, a contact removably held under compression in each insert, interior conformations on the inserts and exterior conformations on the contacts cooperating to position the contacts in the inserts and yieldably resist removal of the contacts, and a conductor wire joining the contacts and extending through the tube, the length of said wire equalling the length of the tube between the points of connection to the contacts and being substantially without slack or slack.

3. The lead of claim 2 in which a said fitting contains a pair of oppositely extending inserts one of which projects into the tube, said inserts having complementary parts of a said cooperating conformation.

4. An electric lead including a protective tube fixed and sealed at each end to a one-piece cylindrical connector shell, said tube and shells constituting a continuous inseparable protective cover for an electric wire and its contacts, an electric wire extending through said tube, contacts fixedly attached to the ends of said wire and positioned, when said wire is fully extended, within said shells, premolded flexible inserts in said shells for compressively holding the said con-

tacts in the shells and sealing the inside of the lead, cooperating conformations on the shells and inserts positioning and yieldably retaining the inserts within the shells, and cooperating conformations on the inserts and contacts positioning and yieldably retaining the contacts in the inserts at the full length of the wire.

5. An electrical lead assembly comprising an elongated tubular conduit, a one-piece fitting at each end of said conduit and permanently secured thereto, a contact carrying insert in each said fitting, said inserts and fittings having cooperating surfaces for positioning and yieldably retaining the inserts in the fittings, a contact member mounted in each insert, said contact members and inserts having cooperating positioning and contact member retaining means thereon, and a cable extending through said conduit and secured at its ends to the adjacent ends of said contact members, said cable being substantially free from slack.

6. An electrical lead assembly comprising an elongated tubular hose, a unitary fitting at each end of said hose and permanently secured thereto, a tubular insert of resilient material in each fitting under radial compression, said inserts and fittings having cooperating engaging surfaces for positioning and yieldably retaining the inserts in the fittings, a contact member mounted in each said insert, said contact members and inserts having cooperating engaging surfaces for positioning and yieldably retaining said contact members in the inserts, the latter exerting pressure radially inwardly against said contact members, and a cable extending through said hose and secured at its ends to the adjacent ends of said contact members, said cable being substantially free from slack.
